William Rosenthal, Culver City, Calif., assignor
to Lynard of California, Inc., Culver City, Calif., a corporation of California

Application March 9, 1953, Serial No. 23,947

Term of patent 7 years

(Cl. D48—20)

To all whom it may concern:

Be it known that I, William Rosenthal, a citizen of the United States of America, residing at Culver City, in the county of Los Angeles, State of California, have invented a new, original, and ornamental Design for a Table Lamp, of which the following is a specification, reference being had to the accompanying drawing, forming a part hereof.

I claim:

The ornamental design for a table lamp, as shown.

WILLIAM ROSENTHAL.
